UNITED STATES PATENT OFFICE

118,025

DESIGN FOR AN ORNAMENT FOR GRAVES

Victor J. Schultz, Chicago, Ill.

Application March 18, 1939, Serial No. 83,672

Term of patent 3½ years

To all whom it may concern:

Be it known that I, Victor J. Schultz, a citizen of the United States, residing at Chicago, in the county of Cook and State of Illinois, have invented a new, original, and ornamental Design for an Ornament for Graves, of which the following is a specification, reference being had to the accompanying drawing, forming part thereof.

I claim:

The ornamental design for an ornament for graves, as shown.

VICTOR J. SCHULTZ.
